UNITED STATES PATENT OFFICE.

HENRY W. SCHLUETER, OF OCEANPARK, CALIFORNIA.

PILE OR COLUMN CONSTRUCTION.

1,165,134.

Specification of Letters Patent. Patented Dec. 21, 1915.

Application filed August 3, 1914. Serial No. 854,872.

To all whom it may concern:

Be it known that I, HENRY W. SCHLUETER, a citizen of the United States, residing at Oceanpark, in the county of Los Angeles, State of California, have invented a new and useful Improvement in Pile or Column Construction, of which the following is a specification.

The invention relates to concrete construction and more particularly to buildings, piers, or the like, which are constructed of reinforced concrete.

The principal object of the invention is to provide a reinforced pile or column which is built up of a plurality of primary members which may be cast at any convenient point and erected in sections, and of secondary members which are cast in place between the primary members.

20 The utility of the invention is obvious to one skilled in the art to which it pertains.

Concrete to attain its maximum strength must be carefully mixed and poured and must be allowed to set under favorable conditions. It is often difficult to provide and maintain such conditions at the point where the work is to be erected. It is especially difficult where the number of pieces involved is large and the time allowed to complete the structure is small. In such a case either a large number of forms must be provided or the members must be assembled before they have time to properly set which is extremely detrimental to their strength. By employing my invention the primary members may be fabricated at any convenient point under controllable conditions and over a sufficient period to insure proper setting and seasoning. The work of 30 erection can then be done quickly and safely by setting the thoroughly seasoned primary members in place and casting secondary locking members therebetween.

Other objects and advantages will be evident hereinafter.

Referring to the drawings which are for illustrative purposes only: Figure 1 is a perspective view of a column embodying my invention. Fig. 2 is an elevation of the 50 head of a column, a portion of the column being shown in section. Fig. 3 is an elevation, partly in section, of a concrete pile embodying my invention. Fig. 4 is a section on the line x^4-x^4 of Fig. 3, an alternative 55 form being shown in dotted lines.

In these drawings, the column consists of a shaft 1 and a head 2, a continuous groove 3 being formed along the inner side of the column having an enlarged area near its base. Longitudinal reinforcing rods 4 are 60 vertically located in the column and are tied together at suitable intervals by horizontal ties 5. The horizontal tie 5 consists of a long member 6 running around the outside of all of the vertical reinforcements 4 and 65 a series of short rods 7, 8, and 9 tying the vertical reinforcements together in pairs.

The method of erecting the invention is as follows: Two primary members, such as are illustrated in Fig. 1, are stood with their 70 inner edges together as illustrated in Fig. 4, and vertical reinforcements 10 tied together by lacing members 11 are placed in the two grooves 3 which adjoin each other and form a closed cavity. Concrete is then 75 poured into this cavity completely filling same and forming a secondary locking key tying the two primary members firmly together and making a homogeneous structure. If desired the column may be extended as 80 shown in dotted lines in Fig. 4, and two secondary keys employed.

The invention has an especial utility in connection with piling used for supporting piers and the like. When used in this connection the primary members are driven into position and the keys are placed on top of a body of broken stone 12 which is first tamped down in the grooves 3.

Where additional structure is to be erected 85 on top of the piers or columns the vertical reinforcements 10 are allowed to extend above the top of the column as shown at 13 and the supporting structure is erected thereon and tied thereto.

90 I claim as my invention:

1. A column having a trough-like recess in one side thereof, vertical reinforcing members embedded in said column about said trough like recess, and horizontal tie 100 members connecting said vertical reinforcing members in pairs, the horizontal tie members being closely adjacent to the sides of the trough like recess and each tie member serving to reinforce one side of the 105 trough like recess.

2. A reinforced concrete column comprising a concrete member having a longitudinal groove in one side thereof, a series of vertical reinforcing members embedded in 110

said concrete around the outer edge of the column, and a series of horizontal tie members rigidly connecting the vertical reinforcing members in pairs, the horizontal tie members being closely adjacent to the sides of the groove and each tie member serving to reinforce one side of the groove.

In testimony whereof, I have hereunto set my hand at Los Angeles, California, this 24th day of July, 1914.

HENRY W. SCHLUETER.

In presence of—

FRED A. MANSFIELD.

F. W. HARRIS.
